WHEELED GOLF CLUB CARRIER

Stuart Thomas Guthrie Murray, Bray-on-Thames, and Maurice John Gillings, London, England, assignors to Murray Components Limited, London, England

Filed June 11, 1971, Ser. No. 152,471

Claims priority, application Great Britain Dec. 11, 1970

Term of patent 7 years

Int. Cl. D12—02

U.S. Cl. D14—3

FIG. 1.

FIG. 2.

FIG. 3.

FIG. 4.

FIG. 1 is a perspective view of a wheeled golf club carrier showing our new design, the view showing the front and one side thereof;

FIG. 2 is a rear perspective view thereof;

FIG. 3 is a front elevational view thereof; and

FIG. 4 is a side elevational view thereof, the opposite side being substantially a mirror image as indicated by FIG. 1.

We claim:

The ornamental design for a wheeled golf club carrier, as shown and described.
